UNITED STATES PATENT OFFICE.

JOSEPH L. KOST, OF GALVESTON, TEXAS, ASSIGNOR OF ONE-HALF TO JAMES H. SHIVELY, OF GALVESTON, TEXAS.

MAIL-HANDLING DEVICE.

1,239,492.

Specification of Letters Patent. Patented Sept. 11, 1917.

Application filed November 16, 1916. Serial No. 131,741.

To all whom it may concern:

Be it known that I, JOSEPH L. KOST, a citizen of the United States, residing at Galveston, in the county of Galveston and State of Texas, have invented certain new and useful Improvements in Mail-Handling Devices, of which the following is a specification.

This invention relates to an improved mail catcher and the principal object of the invention is to provide an improved type of train device so mounted in the car that it may be extended through the door at either side of the car, a further object being to provide an improved means for moving the arms or crane and to provide the same with an improved catching hook and to further provide an improved type of station device for holding a sack to be delivered and for removing a sack from a train, a still further object being to provide an improved type of sack carrying device for holding the sack to be delivered to the train or at the station.

Another object of the invention is to so construct the train device that it will take up a minimum amount of space in the car, it being suspended adjacent the roof of the car and provided with actuating lines by means of which the crane may be moved to extend through either door according to which side of the car, the sack device is positioned.

Another object of the invention is to so construct this crane device that it will be strong and durable and not liable to be damaged when in use.

Another object of the invention is to so construct the sack holding chain and collecting hook that the mail bags will not be injured or the contents thereof injured when taken up or delivered.

This invention is illustrated in the accompanying drawings, wherein:—

Figure 1 is a view showing the car in vertical transverse section and the train device and station device in side elevation.

Fig. 2 is a sectional view taken along the line 2—2 of Fig. 1, the car being shown in longitudinal transverse section and the car device and station device in top plan.

Fig. 3 is a sectional view taken along the line 3—3 of Fig. 2 with the crane or arm shown in elevation and the track in section.

Fig. 4 is a transverse sectional view through the track and crane.

The car device is provided with a housing or track 10 which is suspended from the cross beams 11 of the car 12 by means of the yoke or hanger 13 and is provided with inwardly extending flanges 14 between which are rotatably mounted, the pulleys 15 and 16. The crane arm or carrier 17 is slidably mounted in the housing 10 and is provided with rollers or casters 18 which engage the upper wall of this housing as shown in Fig. 3. This crane or carrier bar extends beyond the ends of the housing and is provided at each end with clips 19 and 20 secured to the opposite side face of the carrier bar from the shoulder 21. A hook 22 which is formed of rod metal such as heavy wire or the like is connected to the side face of this shoulder by means of the fasteners 23 which pass through the eyes 24 at the ends of the arms 25 and is provided with a twisted neck 26 carrying the head 27 which head terminates in a bill 28 bent as shown in Figs. 2 and 3. These hooks 22 extend below and upon opposite sides of the crane or carrier bar as shown in Fig. 2, and it will thus be seen that when one end of the carrier bar is extended as shown in this figure the hook 22 will be extended toward the forward end of the car. Therefore if the car is traveling in one direction, the carrier bar would be extended out one side of the mail car and if it is traveling in the opposite direction, the carrier bar would be extended out of the opposite side door of the car. In order to move the carrier bar there has been provided lines 29 and 30 which extend over the rollers of the double pulley 31 and are then carried toward the ends of the housing 10, passed around the pulley wheels 32 and after passing around these pulleys 32 are carried over the pulleys 15 and 16 and connected with the carrier bar upon opposite sides of the center thereof. It will thus be seen that by drawing upon the line 29 the carrier bar can

be moved in one direction and that by pulling upon the line 30, the carrier bar can be moved in the opposite direction.

The station device includes a platform 33 reached by a flight of steps 34 and having arms or standards 35 and 36 extending above it. The standard 35 carries supporting hooks 37 which extend as shown in Figs. 1 and 2 so that a chain 38 may be suspended in the path of travel of the hooks 22 of the car device. This chain 38 is provided with hooks 39 with which the mail bag or bags 40 will be connected and thus suspended between the standards 35. It will thus be seen that when a train passes a station, the hooks 22 will engage the chain 38 and remove it from the hooks 37 thus collecting the mail bag or bags suspended from the chain. The mail bags to be delivered to the station will be connected with a similar chain suspended from the carrier bar by means of the clips 19 and 20 and as the train passes the station, the hooks 41 carried by the standards 36 will pass through this chain and thus remove the chain from the clips 19 and 20 and leave the mail bags to be delivered at the station suspended from the standard 36. Therefore the mail bag will not be engaged and the mail bag and contents thereof cannot be injured either by a blow struck the bag or by the bag being accidentally punctured. After the mail bag has been delivered at the station and the mail bag to be collected taken from the station by the hooks 22, the carrier bar or crane will be drawn inwardly by drawing upon the proper line 29 or 30 and the chain carrying the bags collected can then be easily disconnected from the hooks. It will thus be seen that a very convenient device has been provided for transferring mail bags from a train to a station or from a station to a train and further that a train device has been so constructed that it will be simple in construction and so made that it will be strong and durable and

not liable to easily break or get out of order. It should be further noted that the shoulders 21 serve as means for limiting the sliding movement of the carrier bar through engagement with the side walls of the housing. 50

What is claimed is:—

1. A mail handling device including a station device comprising a platform, a set of standards extending above said platform, collecting hooks extending from the standards and extending above the standards and toward each other, a second set of standards extending above said platform, and suspending hooks extending from the second set of standards toward each other for suspending a sack between the second set of standards. 55

2. A mail handling device including a station device comprising a platform, a set of standards extending above said platform, collecting means carried by said standards, a second set of standards extending above said platform, suspending means extending between the second set of standards and terminating in spaced relation, a flexible carrier 60 65 carried by said suspending means and provided with an engaging element whereby a sack may be suspended from the flexible carrier. 70

3. A mail handling device including a station device, said station device including a set of standards, collecting means carried by the standards and extending between the same, a second set of standards positioned in alignment with the first set of standards, 75 and suspending means carried by the second set of standards and extending between the same and positioned in a different plane from the plane of the collecting hooks. 80

In testimony whereof I affix my signature 85 in presence of two witnesses.

JOSEPH L. KOST.
